2,369,950

SPRAYING APPARATUS

Thomas Harry Daly, Watervliet, Mich.

Application July 18, 1942, Serial No. 451,481

9 Claims. (Cl. 299—37)

This invention relates to improvements in spraying apparatus.

The main objects of this invention are:

First, to provide a power spraying apparatus for spraying orchards, vineyards, and the like which is highly efficient and may be operated by a single person, manual labor being reduced to a minimum.

Second, to provide a spraying apparatus which may be readily adjusted to vary the throw or sweep of the spray heads and to direct the same.

Third, to provide a spraying apparatus which is simple yet sturdy in its parts and may be applied or adapted to sprayer outfits comprising vehicles or carriages, power units, and pumps of types now in use.

Objects relating to details and economies of the invention will appear from the description to follow. The invention is defined and pointed out in the claims.

A preferred embodiment of the invention is illustrated in the accompanying drawing, in which:

Fig. 1 is a fragmentary side elevation of a spraying apparatus embodying my invention, the standard being shown in collapsed position and various parts being shown conventionally.

Fig. 2 is an enlarged fragmentary view partially in vertical section showing various structural details.

In the embodiment of my invention illustrated, the carriage designated generally by the numeral 1 is designed to be drawn by a tractor or horses or hitched to a propelling vehicle, the hitch not being illustrated. An internal combustion engine is conventionally illustrated at 2, 3 being the gasoline tank and 4 the radiator. A pump is conventionally shown at 5 and has driving connection with an agitator within the tank 6, the driving connection being shown at 7.

At the rear of the carriage, I mount a supporting frame 8 for a standard or upright designated generally by the numeral 9 which has a stepped bearing 10 whereby it is rotatably supported. A worm gear 11 is secured to the standard at the lower end thereof.

A manually driven adjusting worm 12 is supported to coact with this worm gear 11, the shaft 13 of the worm 12 being supported by the bearing 14 adjacent the worm, the shaft 13 having a universal joint connection 15 to the shaft 16 which is manually driven either by a crank or hand wheel, not shown, the shaft 16 being extended so that its operating means is convenient to the operator controlling the tractor or other means.

The standard 9 in the embodiment illustrated comprises a base section 17 and a top section 18 collapsibly connected to the base section by means of the pivot 19 and the clamp 20, the clamp

being adapted to embrace the upper end of the base section when the collapsible section is in erected position as indicated by dotted lines in Fig. 1, and thus connected, a rigid connection is provided.

In this embodiment illustrated, I provide a pair of spray heads 21, these illustrated being of the multiple nozzle type. These spray heads are carried by tubular arms or spray pipes 22 which are connected by the flexible hose or conduits 23 to the source of supply under pressure, a pressure pump in this embodiment.

The arms 22 are engaged by the clamp 24 of the bearing members 25 engaging the pivots 26 which are carried by collars 27 adjustably secured to the standard by means of set screws 28. It will thus be noted that the pivots may be adjusted vertically on the standards and the arms 22 may be adjusted longitudinally relative to the pivots 26 by means of the clamps 24. By adjusting the arms 22 longitudinally, the stroke of the spray heads or the arc of movement of the spray heads may be varied.

The driving means for the sprayer arms or pipes 22 comprise a pair of beveled gears 29 and 30 which are rotatably mounted on the standard. The beveled gear 29 is provided with a hub 30, the gear 29 being arranged on this hub and secured to the gear 28 back to back.

30 A crank gear 31 is mounted on the stub shaft 32 extending from the collar 33 secured to the standard by means of the set screw 34. This crank gear has a crank pin 35 connected to a pin 36 on the spray head arm mounted on the base section of the standard by means of the connecting rod 37. The pin 36 is carried by a collar 38 which is secured in its adjusted positions longitudinally of the arm 22 by means of the set screw 39.

40 The link 40 connects the lower spray head arm to the upper spray head arm, the collar 38 being provided with ears to receive a pin 41 which engages an eye 42 in the link 40, providing a readily detachable connection and permitting the collapsing of the upper section of the standard for storage or in transporting articles from one place of use to another.

45 The supply pipes 33 are controlled by valves 43, a remote control rod 44 being provided for these valves.

50 The crank gear is driven from the power plant, the driving connections comprising a beveled driving pinion 45 which meshes with the downwardly facing gear 28. This gear 45 is connected by the sprocket chain 46 and the sprocket wheels 47 and 48 to the shaft 49 which is controlled by the manually controlled clutch 50, the remote control rod 51 being provided for that purpose.

55 With this arrangement of parts, the apparatus is in complete control of the operator and a

single operator may operate the tractor or other propelling means and control the spray heads as to direction, this being accomplished through the manually actuated shaft 16. The driving worm for this adjustment constitutes an effective lock for retaining the standard in an angularly adjusted position, at the same time it permits easy and sufficiently rapid adjustment to vary the direction of the sprayers. They are automatically swung vertically in any position of their adjustment and the angular adjustment in no way affects their operation and does not place them under any stress. The throw of the sprayers may be varied as has been described.

I have illustrated and described my spraying apparatus in an embodiment which I have found very practical. I have not attempted to illustrate or describe certain embodiments which I contemplate as it is believed that this disclosure will enable those skilled in the art to embody or adapt my invention as may be desired.

Having thus described my invention, what I claim as new and desire to secure by Letters Patent is:

1. The combination in a spraying apparatus, a rotatably mounted standard, said standard comprising a base section, and a top section collapsibly mounted on said base section but constituting a substantially rigid extension of the base section when in erected position, spray heads provided with tubular arms pivotally mounted on said standard, one of the spray heads being mounted on the base section of said standard and another on the collapsible section thereof, flexible supply connections for said spray head arms, connected upwardly and downwardly facing beveled gears rotatably mounted on the base section of said standard, a driving beveled gear coacting with the downwardly facing beveled gear, a stub shaft mounted on the base section of said standard, a beveled crank gear mounted on said stub shaft to coact with the said upwardly facing beveled gear, a connecting rod for said crank gear to the spray head arm mounted on the lower section of said standard, and a link connecting the spray head arm mounted on the collapsible portion of said standard to the spray head arm mounted on the lower portion of said standard, said link having a detachable connection to the lower spray head arm.

2. The combination in a spraying apparatus, a rotatably mounted standard, spray heads provided with tubular arms pivotally mounted on said standard in vertically spaced relation, flexible supply connections for said spray head arms, connected upwardly and downwardly facing beveled gears rotatably mounted on said standard at the bottom thereof, a driving beveled gear coacting with the downwardly facing beveled gear, a stub shaft mounted on said standard, a beveled crank gear mounted on said stub shaft to coact with the said upwardly facing beveled gear, a connecting rod for said crank gear to the lower spray head arm, and a connecting link for the spray head arms.

3. The combination in a spraying apparatus, a rotatably mounted standard, a spray head provided with an arm pivotally mounted on said standard, a flexible supply connection for said spray head arm, connected upwardly and downwardly facing beveled gears rotatably mounted on the base section of said standard, a driving

beveled gear coacting with the downwardly facing beveled gear, a stub shaft mounted on said standard, a beveled crank gear mounted on said stub shaft to coact with the said upwardly facing beveled gear, and a connecting rod for said crank gear to the spray head arm.

4. A spraying apparatus comprising a standard, a spray head provided with an arm pivotally mounted on said standard and vertically adjustable thereon, said arm being longitudinally adjustable relative to its pivot, a pair of connected oppositely disposed beveled gears rotatable on said standard, a beveled driving gear coacting with the downwardly facing beveled gear, a beveled crank gear mounted on said standard to coact with the upwardly facing beveled gear, and a connecting rod for said crank gear to the spray head arm, the connecting rod on said spray head arm being mounted for adjustment longitudinally thereof.

5. A spraying apparatus comprising a standard, a spray head provided with an arm pivotally mounted on said standard, a pair of connected oppositely disposed beveled gears rotatable on said standard, a beveled driving gear coacting with the downwardly facing beveled gear, a beveled crank gear mounted on said standard to coact with the upwardly facing beveled gear, and a connecting rod for said crank gear to the spray head arm.

6. A spraying apparatus comprising a standard, a spray head provided with an arm pivotally mounted on said standard and vertically adjustable thereon, said arm being longitudinally adjustable relative to its pivot, a driven crank member mounted on said standard, and a connecting rod for said member to the spray head arm, the connecting rod on said spray head arm being mounted for adjustment longitudinally thereof.

7. A spraying apparatus comprising a standard, a spray head provided with an arm pivotally mounted on said standard, said arm being longitudinally adjustable relative to its pivot, a driven crank member mounted on said standard, and a connecting rod for said member to the spray head arm, the connecting rod on said spray head arm being mounted for adjustment longitudinally thereof.

8. A spraying apparatus comprising a rotatably mounted standard, a spray head provided with an arm pivotally mounted on said standard, a driven gear surrounding said standard and rotatable independently thereof, a crank gear bodily rotatable with said standard and operatively associated with said driven gear, and a connecting rod for said crank gear to said spray head arm.

9. A spraying apparatus comprising a rotatably mounted standard, a spray head provided with an arm pivotally mounted on said standard, the pivotal axis of said arm being disposed transversely of the rotating axis of the standard, a first and a second gear both said gears surrounding said standard and rotatable independently thereof, said first gear being connected to rotate said second gear, a driving gear meshing with said first gear to rotate the same, a crank gear bodily rotatable with said standard and rotated by said second gear, and a rod for connecting said crank gear to said pivotally mounted arm to oscillate the same and said spray head.
